SOUND RECORDER AND REPRODUCER

Max Bender, Astoria, N. Y., assignor, by mesne assignments, to United Acoustigraph Corporation, a corporation of Nevada

Application July 8, 1933, Serial No. 679,465

1 Claim. (Cl. 179—100.41)

This invention relates to a recording and reproducing of sound, and has for its object an improved apparatus for recording sound in the form of a groove in relatively hard material, such for example, as celluloid or motion picture film. A further object is to provide an improved device which may be used alternately as a sound recorder and reproducer. A further object is to provide an improved form of cutting stylus.

10 Other objects and advantages of my invention will appear from the following description taken in connection with accompanying drawing, wherein;

Figure 1 is a top plan view of a sound recorder and reproducer embodying one form of my invention;

Figure 2 is a sectional view partly in elevation taken on the line 2—2 of Figure 1 and also 2—2 of Figure 3, and showing in addition an anvil with a strip of film thereon;

20 Figure 3 is a sectional view taken on the line 3—3 of Figure 2;

Figure 4 is a sectional view taken on the line 4—4 of Figure 2;

25 Figure 5 is an enlarged detail view showing the relative position of the movable, stylus operating, armature and the pole pieces between which the armature vibrates;

Figure 6 is a greatly enlarged side elevation of an improved form of a cutting stylus;

30 Figure 7 is a bottom plan view of the structure shown in Figure 6;

Figure 8 is a sectional view taken on the line 8—8 of Figure 6;

35 Figure 9 is a circuit diagram of the electrical connections through the armature operating coils; and

Fig. 10 is a plan view of an armature and stylus holder showing a modification.

40 Referring more particularly to Figures 2 to 4 inclusive, reference character 10 represents a permanent horse-shoe magnet which is adapted to be supported by a plate 11 of brass or other non-magnetic material bolted or screwed at 12 to the ends of the poles of the magnet 10. Plate 11 is provided with elongated openings 13 by which the recorder may be adjustably secured in suitable support.

45 Secured to the sides of the permanent magnet 10 by cement or any other suitable manner and extending inwardly therefrom are four coils, 14, 15, 16 and 17 respectively, arranged as shown in Figure 4. Each of the coils has an adjustable core 18, preferably of soft iron, forming at their inner ends two pairs of opposing pole pieces. The

opposite end of each core is extended and screw threaded, and is adapted to be received in screw threaded opening 22 in the side of the permanent magnet 10, thus providing for the adjustment of the core.

5 Positioned between the pole pieces of each pair and adapted to vibrate on a vertical axis is an armature 25 of soft (Norway) iron. Armature 25 is supported by adjustable pivot bearings 27 and 28, secured respectively in the plate 11 and in a brass plate 29 attached at opposite ends to the sides of the permanent magnet 10, the armature preferably being provided pivot cups of hardened steel.

15 Plate 11 at opposite sides of the bearing 27 is formed with openings 30 and 31 through which extend downwardly projecting parts 32 and 33 of the armature 25. The part or extension 32 of the armature carries at its lower end a recording stylus 34 and extension 33 of the armature may, 20 if desired, carry at its lower end reproducing stylus 35.

25 Mounted at one side of the permanent magnet 10 and extending inwardly therefrom at opposite sides of the pivotal axis of the armature are adjustable cushioning means, consisting of non-magnetic screw threaded rods 40 received in screw threaded openings 41, and adjustably held in place by lock nuts 42. The inner ends of the rods 40 are formed as cups 45 which contain rubber or other cushioning material 45a which extends outside of the cup and is constantly in contact with the side of the armature 25. It is to be noted that the armature in horizontal cross section is slightly tapered outwardly from its axis. 30 By forming the armature in this way, I find that I obtain more satisfactory contact of the armature with the pads and a more satisfactory operative relationship of the armature to the pole pieces, and at the same time provide sufficient 35 material at the center of the armature for its adequate support on the pivot bearings.

40 In Figure 2 I show an anvil 50 over which extends a strip of film 51, which is adapted to be moved in the direction of the arrow 52 during 45 the recording operation. After a record is made, it may be reproduced by adjusting the plate 11 so that the reproducing stylus 34 rests in the groove of the film. Occasionally it is desired to record a groove on a film by moving the film in one direction, and then continue the recording by moving the film in the opposite direction. When this is done, I mount a recording stylus at the ends of both extensions of the armature as shown, for example, in Fig. 10, the stylus 55

carried by one extension 32 being adapted to record while the film is moved in the direction of the arrow 52 of Fig. 2 and the stylus carried at the end of the other extension being adapted to record when the film is moved in the opposite direction.

It will be noted from Figure 9 that the coils 14 to 17 are so wound as to tend to make opposite poles of each pair of opposite sign, a north pole being opposite to a south pole and also corresponding poles of the two pair are of opposite sign.

Referring to Figures 6 to 8, the recording stylus 34 is cemented into an opening 61 in lower end of the armature extension 32. This stylus, which is of hard material such as sapphire or diamond, consists of a cylindrical shank 63 which is tapered as indicated at 64. One side of the tapered surface is ground away to form a concave tapered surface 66 of the stylus, this surface in the position of the recorder shown being an upper surface, and beneath this surface the taper is ground away to form two lower concave surfaces 67, leaving between them a portion 68 of the original tapered surface 64. The effect of grinding or under-cutting to form surfaces 67 is to sharpen the curved edge 69 at opposite sides of the axis of the stylus where the upper surface 66 meets the lower surface of the stylus. As the tapered surface 64 is conical it is a comparatively simple operation to grind away this surface to a proper depth. The angle "a" between the upper surface 66 and the portion 68 of the tapered surface 64 should be between 25° and 40° maximum. The angle "b", as shown in

Figure 8, between the surface 67 and the upper surface 66, should be between 20° and 30° maximum. I find that by forming the stylus in this manner, with the angles above given, I not only secure satisfactory cutting but there is sufficient material back of the cutting edge to properly strengthen the stylus and minimize the breakage. In making a sound groove of the lateral type, the angle between the surface 68 and the tangent to the film at the cutting point should be approximately 25°.

It will, of course, be understood that during the recording operation current which varies in accordance with the sound waves to be recorded is passed through the coils 14 to 17 inclusive. The variation may be generated by a suitable monophone actuated by the source of sound and the monophone current amplified by thermionic valves. In reproducing, the coils 14 to 17 will be energized from a source of constant potential and the variations of current produced by vibrations of the armature 25 suitably amplified and reproduced as sound. The stylus as described makes a clean cut in the film, removing from the film a fine thread of the film material.

Having now described my invention, what I claim and desire to secure by Letters Patent is:

In a device of the character described, a magnet having opposite poles, a flat U shaped member of magnetic material pivotally supported at approximately the center of the bend of the U, and the bend of the U being located between and under the influence of said poles, and a stylus secured directly in the end of each leg of the U.

MAX BENDER.
